Filed Jan. 8, 1962, Ser. No. 68,212

Term of patent 14 years

(Cl. D33—3)

FIGURE 1 is a front perspective view of a book end embodying my design wherein the upright is substantially square, the fluted front portion has three grooves and, the terminal end of the rearwardly extending base member is rounded.

FIG. 2 is a rear three-quarter perspective view thereof.

FIGURE 3 is a front perspective view of the book end of FIGURE 1 wherein the upright is rectangular, the fluted front portion has four grooves and, the terminal end of the rearwardly extending base member is squared.

FIGURE 4 is a rear three-quarter perspective view of the embodiment of my new design shown in FIGURE 3.

I claim:

The ornamental design for a book end, as shown and described.
